W. S. Strawbridge
J. Bonsall Taylor.

UNITED STATES PATENT OFFICE.

GEORGE H. PERKINS, OF PHILADELPHIA, PENNSYLVANIA.

NAILING-MACHINE.

SPECIFICATION forming part of Letters Patent No. 240,331, dated April 19, 1881.

Application filed June 21, 1880. (No model.)

To all whom it may concern:

Be it known that I, GEORGE H. PERKINS, of Philadelphia, Pennsylvania, have invented an Improvement in Nail-Holders for Box-Nailing and other Nailing Machines, of which the following is a specification.

My invention relates, in general, to a class of devices employed in machinery for nailing boxes or driving pegs and nails in various material. It relates more specifically to mechanisms employed to receive, retain, and present the nail or peg in proper position to both be acted upon by the driving devices or plungers, and to be entered into the material to be united.

Although of general applicability to pegging and nailing machines, I have in this specification described my invention as embodied in a nail-holder for box-nailing machinery. The nails intended to be employed in the form of holder represented are ordinary headed box-nails.

In the accompanying drawings, Figure 1 is a front elevation of a convenient embodiment 25 of my device, showing the nail-holder, plunger, and plunger-carrier guide. Fig. 2 is a side sectional elevation of the same; Fig. 3, a top sectional view of the same on the line *a a* of Fig. 2; Fig. 4, a top sectional plan on the 30 line *b b* of Fig. 2; Fig. 5, a sectional side elevation of a convenient means of securing a plunger rigidly within its carrier; Fig. 6, a similar view of the same on the line of division of the threaded butt of the plunger.

35 A are cross-bars, secured to the frame-work of any nailing-machine.

B is the carrier-guide, through which the plunger-carrier reciprocates, the same being a journal of any suitable construction.

40 C is a clamp-plate, arranged to bear against the cross-bars A, and adapted, by means of the bolts D, to retain the carrier-guide fixedly upon the cross-bars.

E is the plunger-carrier, being a rod made 45 either square or provided with a feather, and so fitted within the guide B as to be prevented from rotating therein.

F is a wrist-pin, adapted to receive the connecting-rod or other device, whereby a reciprocating motion is imparted to the plunger-carrier. The guide B is slotted longitudinally

upon its rear face, to permit of the reciprocation of the wrist-pin F.

It is obvious that the carrier-guide B can be adjusted laterally at an angle upon the cross-bars by loosening the bolts D, adjusting it to the desired inclination, and retightening the bolts, the clamp-plate securing it at the desired lateral angle upon the tightening of the latter.

60 G are depending brackets from either side of the carrier-guide, which pass down and sustain the nail-holder proper.

H is the plunger, secured to the lower extremity of the plunger-carrier E. The attachment of these parts may be effected in any desired manner. I have, however, devised the following means of securing the plunger in such manner that it cannot shake loose in the action of the machine—that is to say, I split 70 the threaded butt I of the plunger entirely through, as at J, and provide a key or wedge, K, below the threaded butt and in the head of the plunger, which, after securing the butt in place, I tighten up so as to wedge apart the 75 threaded halves of the butt, and thereby retain them rigidly within their socket in the plunger-carrier.

75 The brackets G unite at a point marked *g'*, to form a depending holder-block, L, to which 80 is secured the nail-holder M, the latter being a piece of metal wrapped around upon itself to form a funnel-shaped device, provided with wings m, which embrace the holder-block on either side.

85 N is a transverse pivot, set through the block L and supporting the nail-holder by passing through oblique slots O, cut in either wing of the same. The sole support of the holder to the block L is by means of this pivot 90 and the slot in the wings, and the arrangement is such that as the nail is forced down through the holder the latter is enabled to move upwardly and outwardly, to permit (in conjunction with the springs hereinafter referred to) the passage of the nail. The wings of the holder are joined together to the rear of the holder-block by a filling-up piece, *m'*, Fig. 4, for convenience, and to better secure the holder to the block.

95 P is a spring hung on a stud, Q, within the block, which extends down the length of the 100

holder and within the same, being doubled back at its lower extremity to form a toe, R, which is provided with a catch, r, engaging with the base of the holder-block and limiting the throw of the spring.

S is a nail-feeding tube, located in such manner as to open and discharge its nails, one by one, into the holder, and so relatively placed with regard to the plunger as not to hinder the 10 action of the same.

Such being the construction of my invention, it is obvious that when a nail has been fed into the holder it will rest within the same and be caught between the front side and the spring.

15 Upon the descent of the plunger it encounters the head of the nail, and the nail is forced through between the holder and its spring, the spring being compressed and the holder moved or lifted upwardly and outwardly. 20 Upon the return of the plunger, after the driving of any given nail, the spring and the nail-holder resume their former positions, a new nail is fed, and the action is repeated.

It is obvious that my device, being made 25 in a continuous whole—that is to say, the nail-holder proper, the plunger, plunger-carrier, and carrier-guide being all united together—is adapted to be set at any desired angle on either side of the perpendicular, where- 30 by the nails can be driven at any desired angle, instead of being in every case driven vertically. I consider this adjustability of the device its most important feature, as the device is not only not limited in its adjustability to a 35 given angle, but is adapted to many and varying angles, while, when desired, the device can be fastened perpendicularly, so that the nails are not driven at an angle, but driven straight.

It is also obvious that the construction of the 40 nail-holder is such as to permit the passage and accurate driving of nails of varying sizes, the adjustment of the spring and funnel being such that varying sizes are retained prior to the action of the plunger, and subsequently

permitted to be driven through with equal cer- 45 tainty.

The device is of very simple construction, can be manufactured cheaply, is not liable to get out of order, and is of such construction that certainty of action is insured.

Having thus described my invention, I 50 claim and desire to secure by Letters Patent of the United States—

1. The carrier-guide B, containing a plunger or a carrier thereof, and adapted to be secured at varying lateral angles to the frame-work of a nailing-machine, in combination with the nail-holder M, whereby the nail-holder assumes the same angle with the carrier-guide, substantially as set forth.

2. In a nailing-machine, as a device to enable the placing of the nail-holder and nail-driving mechanism at lateral angles, the clamp-plate C, in combination with the carrier-guide B, and with the cross-bars A, or other fixed portion of the frame-work, by means of tightening-up bolts D, which act to cause the clamping at the desired angle of both clamp-plate and carrier-guide upon the cross-bars, substantially as shown and described.

3. As a device for retaining and permitting the discharge of nails of varying sizes, a tubular receptacle or nail-holder, M, provided with an inclosed spring, P, and fitted with wings m, slotted at O, in combination with a holder-block, L, having a pivot, N, substantially as shown and described.

4. As a device for permitting the upward and outward movement of the nail-holder proper, the oblique slots O in the wings of the 80 nail-holder, in combination with the transverse pivot N in the holder-block.

In testimony whereof I have hereunto signed my name this 1st day of May, A. D. 1880.

GEORGE H. PERKINS.

In presence of—

C. B. TAYLOR,
J. BONSALL TAYLOR.
